UNITED STATES PATENT OFFICE.

HERBERT S. WILSON, OF ST. LOUIS, MISSOURI.

PROCESS OF FORMING PAPER RECEPTACLES.

1,015,370.

Specification of Letters Patent.

Patented Jan. 23, 1912.

Application filed March 14, 1910. Serial No. 549,199.

To all whom it may concern:

Be it known that I, HERBERT S. WILSON, a citizen of the United States, residing at the city of St. Louis, Missouri, have invented 5 a certain new and useful Process of Forming Paper Receptacles, of which the following is such a full, clear, and exact description as will enable any one skilled in the art to which it appertains to make and use the 10 same, reference being had to the accompanying drawings, forming part of this specification.

My invention relates to a process for forming paper receptacles and more particularly for forming water-proof receptacles for containing liquids and the like. Such water-proof receptacles are usually formed by coating the paper with melted paraffin. One difficulty in forming tubes 20 from such paper is that the paraffin is not adhesive until it begins to harden and consequently there is great difficulty experienced in retaining the paper in cylindrical form while the paraffin is hardening.

25 The object of my invention is to overcome the above difficulty and this I do by curling one end of the sheet of paper from which the tube or cylinder is to be formed and then rolling the paper into form with the 30 uncurled end inside of the curled end so that the tendency of the inner part of the tube to expand and the outer part to contract firmly holds the layers of paper together while the coating hardens.

35 In the accompanying drawings which illustrate one form of apparatus for carrying out my invention, Figure 1 is a diagrammatic view; Fig. 2 is a view of some of the parts shown in Fig. 1 but in different 40 position; Fig. 3 is a diagrammatic view of one of the sheets of paper after being curled; Fig. 4 is a side elevation of the completed receptacles partly in section, and Fig. 5 is a diagrammatic view of apparatus for securing 45 the caps in the receptacle.

10 represents the roll of paper. The strip of paper passes from the roll 10 between the pair of rolls 11 and 12 respectively. The roll 12 may be provided with suitable print- 50 ing characters to print any suitable matter upon the paper. After the strip of paper passes from the rolls 11 and 12 it is cut into suitable lengths by means of a pair of knives 13. From the knives 13 the strip of paper 55 passes to feeding rolls 14. It will be understood that the web of paper is carried for-

ward by conveyers which are not shown as they form no part of the present invention and are fully described in my application referred to below. Beyond these feeding 60 rolls 14 are a second pair of rolls 15. Arranged between the rolls 14 and 15 is a spring blade 16 and a pivoted blade 17 having a sharp edge. During the passage of the first part of the strip of paper between the rolls 14 and 15 the pivoted blade 17 is in the position shown in Fig. 2 so that the first 65 part of the paper is uncurled. When, however, about one-half of the paper has passed beyond the spring blade 16, the blade 17 is moved into the position shown in Fig. 1 so that the remainder of the paper is drawn across the sharp edge of the blade 17 and caused to curl. The strip of paper after 70 this is accomplished, if left to itself, would assume the form shown in Fig. 3, the first half 18 of the paper being uncurled as shown in said figure and the last half 19 curled. After passing from the rolls 15 the paper 75 passes under a roll 20 so as to immerse the paper in a bath 21 of any suitable material for holding the layers of paper together and also preferably water-proofing the paper at the same time. I prefer to use melted paraffin for this purpose.

80 After passing out of the bath 21 the strip of paper passes between a pair of rolls 22 and thence to the mandrel 23 upon which it is wound to form a cylinder or tube. Rolls 24 serve to press the paper firmly against the mandrel. A guard 25 also preferably 85 partially surrounds the mandrel 23. As the uncurled end 18 of the strip of paper is fed first to the mandrel 23 this end of the paper will be rolled inside of the curled end 19. 90 The uncurled end 18 of the paper will tend to expand while the curled end 19 will tend to contract and as the uncurled end is rolled inside of the curled end the contrary tendency of movement of the two parts will hold 95 the layers of paper firmly in position while the paraffin hardens so as to form a tube or cylinder 26. After the tube is formed, a cap 27 as shown in Fig. 4 may be inserted in the end of the tube to complete the package. 100 This end or cap 27 is then immersed in a paraffin bath 28 as shown in Fig. 5. An endless conveyer 29 conveys the packages out of the bath 28 and fans 30 are preferably supplied for cooling the receptacles 26 and 105 thus hastening the hardening of the melted paraffin.

As is set forth in my companion apparatus application referred to below, the wound up laminated tube on the mandrel is removed therefrom before the adhesive has had an opportunity to set and thereafter the preliminary curling given to the paper is utilized to hold together the laminations of the tube while they are being cemented together by the setting or hardening of the adhesive. 5 In other words, the discharged tube retains (during the setting of the adhesive) the form and diameter given to it by the mandrel because of the initial curling of the paper which prevents its unwinding. 10 The apparatus which I prefer to use in carrying out my invention is shown in detail in application Serial No. 522,350, filed by me Oct. 11, 1909. While I prefer to use such apparatus I do not wish to be understood as limiting myself to the use of any particular form of apparatus for carrying out my invention. 15 Having fully described my invention, what I claim as new and desire to secure by Letters Patent of the United States is: 20

1. The process of forming a laminated paper tube moisture-proof throughout substantially its entire thickness, which consists in preliminarily giving a strip of paper 30 a tendency to curl up in a plurality of concentric convolutions, then applying thereto a coating of moisture-proof adhesive, then winding said coated paper strip into tubular laminated form on a cylindrical mandrel, and then removing the tube from said mandrel before the adhesive has had an opportunity to set, the tendency of the paper to curl up after removal of the tube from the mandrel and during the setting of the adhesive causing the laminations of the tube to hug one another and the tube to maintain the form and diameter given to it by the mandrel, substantially as described. 35
2. The process of forming a laminated paper tube which consists in preliminarily giving a strip of paper a tendency to curl up in a plurality of concentric convolutions, then applying thereto an adhesive coating, then winding said coated strip into tubular 40 form on a cylindrical mandrel, and then removing the tube from said mandrel before the adhesive has had an opportunity to set, the tendency of the paper to curl up after removal of the tube from the mandrel and during the setting of the adhesive causing the laminations of the tube to hug one another and the tube to maintain the form and diameter given to it by the mandrel, substantially as described. 45
3. The process of forming a moisture-proof laminated paper tube, which consists in curling a strip of paper to give a portion of the same a more acute curvature than that of the remainder of the strip, applying 50 a moisture-proof adhesive to said strip, and

then winding the strip into tubular form with the portion of sharper curvature outermost whereby the convolutions are held together in position during the setting of the adhesive which secures them together, substantially as described. 70

4. The process of forming a laminated paper tube, which consists in curling a portion only of a strip of paper, and winding the strip into tubular form with the uncurled portion innermost, whereby the convolutions are held together in position by the tendency of the inner convolutions to expand and the outer convolutions to contract, substantially as described. 75

5. The process of forming a laminated paper tube, which consists in curling a portion only of a strip of paper, applying an adhesive to said strip, and winding the strip into tubular form with the uncurled portion innermost, whereby the convolutions are held together in position during the setting of the adhesive securing them together by the tendency of the inner convolutions to expand and the outer convolutions to contract, substantially as described. 80

6. The process of forming a laminated paper tube, which consists in curling a portion only of a strip of paper, supplying a water-proof coating to said strip, and winding the strip into tubular form with the uncurled portion innermost, whereby the convolutions are held together in position by the tendency of the inner convolutions to expand and the outer convolutions to contract, substantially as described. 90

7. The process of forming a laminated paper tube, which consists in curling a portion only of a strip of paper, applying a water-proof adhesive coating thereto, and winding the strip into tubular form with the uncurled portion innermost, whereby the convolutions are held together in position during the setting of the adhesive securing them together by the tendency of the inner convolutions to expand and the outer convolutions to contact, substantially as described. 105

8. The process of forming a laminated paper tube, which consists in curling a portion only of a strip of paper, applying thereto a coating of a melted material which is adhesive when solid and substantially non-adhesive when melted, and winding the strip into tubular form with the uncurled portion innermost, whereby the convolutions are held together in position, during the solidification of the coating adapted to secure the convolutions together, by the tendency of the inner convolutions to expand and the outer convolutions to contract, substantially as described. 115

9. The process of forming a laminated paper tube, which consists in curling a strip of paper by drawing the same across an 120

edge, applying an adhesive to said paper, and winding the strip into tubular form, whereby the convolutions of paper are held in position by their own resiliency during the setting of the adhesive which secures them together, substantially as described.

10. The process of forming a laminated paper tube, which consists in curling a portion only of a strip of paper by drawing the same across an edge, applying an adhesive coating to said strip, and winding the strip into tubular form with the uncurled portion innermost, whereby the convolutions are held together in position during the setting of the adhesive which secures them together by the tendency of the inner convolutions to expand and the outer convolutions to contract, substantially as described.

20. 11. The process of forming a laminated paper tube, which consists in curling a portion only of a strip of paper by drawing the same across an edge, applying an adhesive waterproof coating to said strip, and winding the paper into tubular form with the uncurled portion innermost, whereby the convolutions are held together in position during the setting of the adhesive which secures them together by the tendency of the inner convolutions to expand and the outer convolutions to contract, substantially as described.

25. 12. The process of forming a laminated liquid-proof paper receptacle, which con-

sists in curling a portion only of a strip of 35 paper, then coating the paper with melted paraffin, then winding the coated paper into tubular form with the uncurled end innermost, and then inserting a cap in an end of the tube and immersing the same in a 40 paraffin bath, substantially as described.

13. The method of forming laminated paper tubes from a strip of material such as paper or the like, which consists in feeding forward the strip of paper, severing it 45 transversely to produce blanks of suitable length, curling a portion only of each blank, then passing it through a liquid coating bath, and winding the paper blank into tubular form, substantially as described. 50

14. The method of forming laminated liquid containers from a strip of material such as paper or the like, which consists in feeding forward the strip of paper, severing it transversely to produce blanks of suitable 55 length, curling one end only of the blank, then passing the blank through a liquid coating bath, winding the blank into tubular form with the uncurled end innermost, and applying a closure to one end thereof, substantially as described.

In testimony whereof I have hereunto set my hand and affixed my seal in the presence of the two subscribing witnesses.
